PRESSING MACHINE ELEMENT

Filed April 25, 1929

UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

PRESSING MACHINE ELEMENT

Application filed April 25, 1929. Serial No. 358,140.

This invention relates to pressing machines, as garment and laundry presses, and has for its object a particularly simple and efficient construction of one or both of the pressing elements by which a low pressure fluid, as air, can be blown through the pressing face thereof and the padding to dry the padding and the work thereon and by which a high pressure fluid, as steam, can be projected through the padding and through the garment primarily to steam the garment without steaming the pad or steaming the pad to a minimum extent and the garment to a maximum extent.

15 A further object of the invention is to provide an improved pressing element construction over that shown in my copending application Serial No. 358,139, filed April 25, 1929.

20 The invention consists in the novel features and in the combinations and constructions hereinafter set forth and claimed.

In describing this invention, reference is had to the accompanying drawings in which 25 like characters designate corresponding parts in all the views.

Figure 1 is a plan view, partly broken away, with the padding removed, of a pressing machine element embodying one form of this invention.

30 Figures 2 and 3 are respectively a lengthwise longitudinal sectional view and a transverse sectional view of the pressing element shown in Figure 1.

35 Figure 4 is an enlarged fragmentary view illustrating the relative location of the perforations in the pressing face of the element and the jets for the steam.

40 Figure 5 is a side elevation of a pressing machine embodying this invention.

The machine here illustrated comprises, a head 1 movable toward and from a buck 2, the latter being supported by a suitable goose neck 3 on a frame 4. The head 1 is carried in the usual manner by a yoke lever 5 pivoted between its ends at 6 to a standard 7 rising from the frame. The head is movable toward and from the buck by any suitable mechanism 45 either foot operated or power operated, this

mechanism being connected to the rear arm of the yoke lever 5.

The mechanism here shown comprises a cylinder 8 having a piston therein, the rod 9 of which is connected to one arm of an angle 55 lever 10 pivoted at its angle at 11 to the base of the frame and the other arm of which is pivoted at 12 to one end of a link 13, the other end of which is pivoted at 14 to the rear arm of the yoke lever. The piston is single acting and the press is opened when the pressure in the cylinder is released by one or more countersprings 15. The flow of motive fluid, as air, to and from the cylinder is controlled by any suitable valve means operated by man- 60 uals, as a push button 16 and release lever 17.

The pressing element or buck 2 is the element of the pressing machine provided with my invention and it comprises a body 18 formed with an internal chamber 19 for a low 70 pressure fluid, as air, the upper wall 20 of this chamber being foraminous or formed with perforations 21 substantially throughout its area. This wall 20 forms the pressing face of the buck and is usually covered by a padding 22. The wall 20 is here illustrated as detachably secured to the body 18, as by screws 23 extending through the margin of the plate and threading into the margin of the body. A gasket 24 is usually inserted 75 so between the margin of the plate and the margin of the body 18.

The chamber 19 is provided with a valve controlled inlet 25 for air, which inlet opens through the bottom of the chamber. The 80 body 18 is also preferably formed throughout the greater area thereof with a heating chamber 26 for receiving a heating medium, as steam, from any suitable source.

27 designates conduits for a high pressure 90 fluid, as steam, these being located in the chamber 19 and having comparatively small jet openings 28 arranged in line with the larger perforations 21 and spaced apart from the wall, these jet openings being arranged 95 to discharge the steam jets through some of the perforations 21 and directly through the padding with enough force to penetrate the padding and not spread out through the padding.

In the illustrated embodiment of my invention, there are three conduits 27 extending lengthwise of the chamber 19 along the middle thereof. These conduits are formed with reversely extending end portions 29 located along the outer sides of the chamber 19, these portions 29 being unprovided with jet openings and being closed at their ends. The jet openings 28 are so fine that water can not readily pass through them so that any condensation is carried along the conduits 27 to the portions 29 where it will be reconverted into steam by the heat from the element. The conduits 27 are connected to a header 30 extending through the bottom of the chamber 19, this header being connected to a feed pipe for comparatively high pressure steam, the pipe having a control valve 31 therein of any well known construction.

32 designates the control valve in the air supply conduit 25. This valve is normally closed, and is opened by a pedal 33 pivoted at 34 to the base of the frame and connected to the lower end of a rod 35, the upper end of 25 which is connected to the valve. The pipe 25 is connected to a pipe 36 leading to a suitable source of supply of compressed air, as a blower 36a. The blower is actuated in any suitable manner. The steam valve is operated by a similar pedal lever 37 pivoted on the pivot 34 and connected to a rod 38 which operates the valve head within the valve casing 31.

In operation, when the pedal 37 is depressed, steam enters the pipes 27 from the header 30 and jets through some of the perforations 21, that is, it jets through the perforations 21 with sufficient force to penetrate or pass through the padding and blow and distribute through the garment thereon without distributing through the padding. By depressing the pedal 33, air of comparatively low pressure passes into the chamber 19 and distributes throughout the same and passes through the perforations 21 through the padding and the garment.

This buck construction is particularly advantageous in that it provides a simple and economical way for projecting high pressure steam through fine jet openings and the large perforations 21 and through the padding and the work thereon and also a low pressure fluid as air through the same openings 21, it being understood that large openings suitable for air are too large for projecting steam with any force unless the pressure of the steam is very great. It is impractical in a pressing machine to supply steam at a sufficient pressure to pass through a padding with force through large holes adapted for passing air therethrough.

What I claim is:

1. A pressing machine element comprising a body formed with an internal chamber 65 for a fluid and with perforations opening

from said chamber through its pressing face and a conduit for a fluid under pressure having jet openings in said chamber in line with the perforations and spaced from the inner ends of the perforations. 70

2. A pressing machine element comprising a body formed with an internal chamber for a fluid underlying the pressing face of said element and with perforations opening from the chamber through its pressing face and a 75 conduit for a different fluid having jet openings in said chamber spaced from the inner ends of the perforations and located in position to discharge through said perforations, and valve controlled means for supplying the fluid to the chamber and the conduit respectively. 80

3. A pressing machine element comprising a body formed with an internal air chamber underlying the pressing face of said element and with perforations opening from the chamber through the pressing face of said element, a conduit for steam having jet openings in said chamber alined with and spaced from the inner ends of the perforations to 90 discharge steam through said perforations and valve controlled means for supplying air under pressure to said chamber and steam to said conduit. 85

4. A pressing machine element comprising 95 a body formed with a pressing face having openings therethrough, and means for projecting a fluid through the pressing face including jets for a fluid under pressure, the jets being spaced from the pressing face and 100 located in line with the openings in the pressing face.

5. A pressing machine element comprising a body formed with an internal chamber for a fluid under low pressure and with comparatively large perforations opening from the chamber through the pressing face of the element and a conduit for a fluid under comparatively high pressure having discharge openings of less size than the perforations 110 alined therewith, and spaced from the inner ends thereof and valve controlled means for supplying low pressure air to said chamber and comparatively high pressure fluid to said conduit. 105

6. A pressing machine element comprising a body formed with an internal chamber for a comparatively low pressure fluid and with perforations leading from said chamber through the pressing face substantially 120 throughout the area of said face and a conduit for a high pressure fluid having jet openings of less size than said perforations and alined with some of the said perforations and spaced from the inner ends thereof and 125 means for supplying fluid to the chamber and said conduit.

7. A pressing machine element comprising a body formed with an internal chamber for a comparatively low pressure fluid and with 130

perforations leading from said chamber through the pressing face substantially throughout the area of said face and a conduit for a high pressure fluid having jet openings of less size than said perforations and aligned with some of the said perforations and spaced from the inner ends thereof, a padding overlying the pressing face and means for supplying fluids to the chamber and

10 said conduit.

In testimony whereof, I have hereunto signed my name, at Syracuse, in the county of Onondaga and State of New York, this 18th day of April, 1929.
